SAMUEL J. EVANS, DECEASED.

MACHINE FOR CANCELING LETTERS.

No. 903,069.

Specification of Letters Patent.

Patented Nov. 3, 1908.

Application filed February 21, 1906 Serial No. 302,309.

To all whom it may concern:

Be it known that I, SAMUEL J. EVANS, citizen of the United States, residing at Roanoke, Virginia, have invented certain new and useful Improvements in Machines for Canceling Letters, of which the following is a specification.

My invention relates to machines for canceling and post marking letters, my object being to improve the machine throughout and render its operation certain and effective.

The invention consists of the features and combination and arrangement of parts hereinafter described and particularly pointed out in the claims.

In the drawing, Figure 1 is a plan view of the machine with the parts in normal position ready to receive the letters to be canceled. Fig. 2 is a plan view of the marking and impression means and the device associated therewith for registering the letter and timing the operation of the printing or marking means, showing a letter at α in the act of being canceled, and illustrating also devices associated with the marking and impression means for insuring the proper control of the letters. Fig. 3 is a detail plan view of parts shown in Fig. 2 in a different position showing how the letter is held when it has arrived at an improper time until the marking means has arrived in proper position to act thereon. Fig. 4 is a detail sectional view of the friction feed wheel for the letters, guiding and retarding devices being shown in elevation. Fig. 5 is a detail view of the impression roll or platen showing also the vibrator and means for operating the same and the supplemental guard and its operating means. Fig. 6 is a sectional view through the bed of the machine from front to rear substantially on the line 6-6 of Fig. 1, with parts however shown in side elevation. Fig. 7 is a rear elevation of the machine. Fig. 8 is a detail view of the means for setting the stacker. Fig. 9 is a detail front view of the controlling gate for the letters and parts associated therewith.

The letters to be canceled and post marked are placed on edge upon a table 1, with their forward ends resting against the guard or guide wall 2, extending vertically in relation to the table surface. They are pressed against the feed wheel 3, which is in constant rotation and thereby they are forced one by one into engagement with a friction

feed wheel 4, against which the letter is guided and pressed by a spring finger 5 curved as shown in Fig. 1 to provide a flaring inlet for the letter. This spring pressure finger is pivoted at 6 to a lug on the guard wall 2, and it is pressed by a spring 7 attached thereto and to a bracket 8 so that its rounded or curved end is pressed constantly towards the friction feed wheel 4. A set screw 8^x acts as a stop for the spring pressure finger.

The frictional feed wheel is of special construction and is shown in detail in Fig. 4, and it consists of rubber rings 9 held to the hub or core of the wheel between the flanges 10 and the heads or plates 11 screwed to the core or hub, said hub being loose on the rotating shaft 13 and borne upon frictionally by the plates or disks 12 keyed to the said rotating shaft and the upper plate 12 being 70 borne upon by a spring 13 held within a cap 14 and adjusted as to tension by the nut 15 threaded on the end of the rotating shaft. The frictional contact between the plates 12 and the heads of the feed wheel is so adjusted by means of the spring and nut that when the letters being fed into the machine are momentarily arrested as will be herein-after described the feed means consisting of the rubber rings 9 will remain at rest and 80 will not tear or buckle the letter, whereas when the letter is free to advance through the machine the frictional contact between the parts of the friction wheel will be sufficient to move the letter forward. 90

As will be noticed from Figs. 4 and 7 the rubber feeding surfaces or rings 9 are separated from each other and into the space 16 thus provided the spring finger 5 extends slightly when in normal position Figs. 1 95 and 3.

Opposite the feed wheel a letter retarding block 17 is arranged, this consisting of rubber pieces 19 fixed in sockets 19' of the block 17, one of said rubber pieces being provided 100 for each of the feeding rings 9 of the friction feed wheel.

The spring finger 5 when pressed away from the feed wheel will recede into the space 20 of the retarding block and the relation of the parts is such that the spring finger will act on said letters and cause them to be pressed against the feed surface 9, and they will pass freely forward over the smooth rounded surface of the spring 110

finger, but a second letter on presenting itself to the spring finger 5 and the feed wheel while the first is still there, will, by its added thickness press the spring finger back so far as to cause it to recede into the space 20 of the retarding or separating block and thus exposing the rubber retarders 19 to engage the second letter and hold it until after the first letter has been fed forward, when 10 the spring finger will immediately press the second letter against the feed wheel 4 and away from contact with the retarding blocks or rubbers 19. In this way the letters are separated and fed forward one by one. 15 This retarder or separator 17 is supported upon a standard or arm 17' passing up through an opening 17" in the bed of the machine from a lever 17*, pivoted below the bed at 17*, Fig. 1, a spring 17^b acting on 20 said lever and pressing the separator constantly towards the feed wheel, its movement in that direction however being limited by the stop consisting of a screw rod 17^c journaled beneath the bed and operated 25 by a finger piece 17^d. This yielding quality of the separator or retarder and also of the spring finger 5 accommodates letters of different thickness.

From the feed wheel 4 the letters pass between the feed rollers 21, 22, of which 22 is a driven wheel while 21 is merely a presser wheel, and from these the letter is fed forward to the impression means which comprises the rotary die or head 23 and an impression roller or platen 24. The rotary die or head carries the marking dies 25 for applying the post marks and it also carries the ribs 26 for applying the canceling marks to the letters. Ink is applied to the dies and 30 canceling ribs by an inking roller 27 having a textile covered periphery 28* saturated with ink which is applied to the dies and ribs each time they come around thereto.

The impression roller or platen is moved 45 towards the die roller or head when a letter has arrived in proper position between them so as to register properly with the canceling ribs and the die on the said roller. For securing this registration of the letter in relation to the means to make the impression, I 50 employ a registering device or stop which also acts as a timer for the operations of the impression roller or platen by locking the said platen to its operating mechanism at 55 the proper times. This combined letter stop and locking-key consists of a lever 28 pivoted to a fixed point at 29 to the overhanging portion 30 of a box or bracket 31 secured to the bed of the machine. This lever has 60 one arm 32 extending normally across the path of the letter between the die head and impression roller and the other arm 33 of this lever extends laterally from the housing or bracket 31 to be at times in the path 65 of the end 34 of the vibrator or controller

35 arranged independently and to one side of the impression platen or roller. This vibrator reciprocates in a direction transverse to the path of the letters so as to carry the end 34 from the position shown in Fig. 1 to 70 that shown in Fig. 3 and back again. The locking-key or timing stop 28 is held normally out of the path of movement of the vibrator by a spring 35" as shown in Fig. 1 attached at one end to the locking-key and 75 at the other to a bracket 36 on the housing. When however, a letter is fed between the printing and canceling members as at α Fig. 2 it contacts with the arm 32 of the letter stop or timer and swings the same on its 80 pivot from the position shown in Fig. 1 so that its arm 33 will move out into the path of the vibrator 35 and this arm will be moved forward as a whole with the forward movement of the vibrator, its pivotal movement being limited by the pin 43 as described below, and this action will result in the impression roller being moved forward to force the envelop or letter into contact with the canceling ribs on the die or rotary 90 head and in proper register with said ribs. This result is accomplished as follows: The impression roller has its shaft 24* journaled in a box 37 slidably in an opening 38 in the bed. The lower end of the impression shaft 95 is pivoted to the frame at 39 and it is driven through a gear 96 fixed to said shaft. The upper end of the shaft extends into an opening in bar 41 which is arranged within a barrel or plunger 42 slidably mounted in the 100 housing or box 31 before mentioned. This barrel has its forward end flattened and carries a pin 43 extending upwardly in front of the arm 33 of the letter-registering-stop and locking-key. Now when a letter 105 has arrived at the registering-stop the said stop by pressure of the letter will be turned on its pivot as above referred to so that its arm 33 will be struck by the vibrator 35 and said arm will be moved forward and in 110 this movement it will press upon the pin 43 and through it the barrel 42 and the bar 41 carried thereby will be moved to cause the impression roller to advance and press the letter upon the marking devices on the die 115 or rotary head 23, which letter has, by contacting with the arm 32, been properly registered in place.

As above stated the registering stop for the letter has swinging movement only, its 120 pivot 29 being a fixed point on the housing or box 31 and in the swinging movement above described the registering-stop for the letter acts as a locking-key to lock or connect the impression roller to its actuating 125 mechanism as hereinbefore described, and further, as it continues to swing under pressure due to the advancing movement of the vibrator 35 in the arrow direction Fig. 3 the end of its arm 32 is caused to recede from 130

across the path of the letter and out of contact with the said letter which is thus left free to be moved onward by the combined action of the impression roller and the marking die or roller, it being post-marked and canceled during its passage between said parts.

The full throw of the platen or impression roller towards the die or marking roller 10 or head is such as to mark the letters of minimum thinness and in order to mark thicker letters I have provided means whereby the impression roller may yield when a thicker or heavier letter is going through the machine. For this purpose the bar 41 is shouldered at 44 where it is borne upon by a comparatively stiff spring 45 arranged within the barrel 42 and resting at its rear end upon the end 46 of the barrel. The spring 20 is sufficiently stiff to cause the bar 41 and the platen or impression roller connected therewith to be moved forward as one body when the barrel or plunger is moved forward by the vibrator and locking-key 28, but when 25 extra thick letters are going through the spring 45 will yield and allow the bar 41 to lag behind the plunger or barrel sufficiently to accommodate this extra thickness of the letters. The bar 41 may be adjusted to set 30 the impression roller or platen accurately in position by the nuts 47 on the threaded rear end of the bar.

It will be understood that the vibrator is timed to advance its contacting end 34 in a 35 certain relation to the arrival of the marking devices of the die at the printing point, and as the die carrier or rotary head has two sets of marking devices disposed thereon the vibrator makes two complete oscillations to 40 each revolution of the marking die carrier. Should a letter arrive at the registering-stop arm 32 at an improper time it will be held either by the said stop arm or by a 45 supplemental guard or stop 48 arranged adjacent to but in a lower plane than the registering stop arm 32.

Fig. 3 illustrates the arrival of a letter at the registering stop at an improper time, that is for instance after the contacting end 34 of the vibrator has advanced as shown in 50 said figure beyond the point at which it might engage the end of the registering stop arm 33. At this time it will be noticed that the end of said arm 33 bears upon the plain 55 side of the vibrator which thus holds the registering stop against movement and with its end maintained across the path of the letter to hold the same until such time as the 60 vibrator moves back and picks up the registering-stop or locking-key on its next forward movement, which will thus act to make the registering-stop get in time with the marking roller and cause the letter to be registered with the marking devices and causing also the impression roller to be advanced

at the proper moment. The other contingency that must be guarded against is when a letter arrives and contacts with the main registering-stop 32 when the vibrator is on its backward stroke opposite to the direction 70 indicated by the arrow, or when the vibrator is beginning its forward movement and has not yet arrived with its contacting end to the point of contact with the locking-key. The registering stop would be pressed aside 75 freely towards the right when the contracting end 34 had passed rearwardly in relation to the locking-key and it would allow the letter to be carried on through the machine, or to become misplaced in relation to the marking 80 devices by contact with the rotary die or marking head. In order to prevent the passage of the letter by the printing or canceling members at this time the supplemental 85 stop or guard 48 above mentioned is employed, which has an end adapted to reach across the path of the letter and act in connection with a gate 49 to hold the letter and prevent it from unduly acting against the registering stop or locking-key and slipping 90 past the same until said locking-key is engaged by and under the control of the contacting end of the vibrator. This supplemental stop or guard is oscillated from the position shown in Fig. 1 where it is in contact with the gate 49 to the position shown in Fig. 2 in dotted lines, where it is swung back to allow the letter to pass by the marking devices and the registering-stop. The opening of the guard or supplemental stop 100 48 to the position shown in dotted lines in Fig. 2 is but momentary as it returns quickly to the position shown in full lines in said figures, the effect of which is to push the letter off from engagement with the hook 32* 105 of the arm 32 on which it might hang.

The gate 49 is yieldingly held so that it will recede under the pressure of the letters and more or less according to their thickness. The gate is pivoted at 50 to a bracket 51 and 110 it is pressed by a spring 52 so that its free end is yieldingly pressed away from the periphery of the die head. Its position is limited by a stop screw 53. The gate is shouldered at 54 and when the parts are in 115 position to arrest the free passage of a letter in order to register it with the marking devices the end of the supplemental stop or guard reaches around the corner of said shoulder and bears upon its face. The 120 spring gate is also recessed at 55 to receive the end of the letter-registering-stop arm 32. This gate coacts with both the letter-registering-stop arm 32 and the supplemental guard 48 to prevent the letters slipping by the ends 125 of said parts as it confines the letters closely by contact with their sides as shown in Fig. 3. After passing the marking die and impression roller or platen the letters pass between the delivery rolls 56 and thence to a 130

stacking device 57 carried by the shaft 58, said stacker having a scroll formation as shown in Fig. 1 and having an abrupt drop or shoulder 59. This scroll shaped stacker 5 operates through a fence or shield 60 and the letters arriving from the delivery rolls strike the periphery thereof and are pressed laterally and stacked against the plate 61 which is carried by or supported upon the 10 block 62 supported on the table or chute 63 and which plate is movable along the said chute as the quantity of letters stacked thereagainst increases. The ends of the letters 15 after passing by the stacker strike against the fence or wall 64 extending at an inclination over the table or chute and adjustably held by the slotted bracket and set screw 65—66.

The stacker is composed of a number of sections or scrolls, Fig. 6, like that shown in 20 plan in Fig. 1 carried by the said shaft 58. The abrupt shoulder or drop 59 on the stacker allows the letters to contact with their forward edges close to the center of the rotary stacker and immediately the said 25 letters are operated upon and pressed laterally by the scroll portion of the stacker.

A supplemental stacker is arranged at 70 having a series of rounded projecting portions 71 to engage the extreme end portions 30 of long letters and move them laterally. This supplemental device being more particularly useful in the case of long letters.

Having now referred to the principal elements and the functions performed by them 35 I will revert to the means for actuating these elements.

The vibrator is reciprocated by connections leading to an eccentric 72 on the main shaft 73 of the machine. These connections 40 consist of the rotary shaft or pin 74 formed in one piece with the crank disk 35 which is connected by the pitman or link 35' with the bar 35 constituting the vibrator and which bar is slidably mounted in the housing 31. 45 The lower end of the said shaft 74 bears in a bracket or frame part 75 and having an arm or block 76 clamped thereto by the bolts 77, the said arm being connected by a right angular link 78 with the rod 79 of an eccentric strap 80 which is operated by the eccentric 72 on the main shaft 73 above mentioned. This eccentric rod has a yielding connection 50 with the eccentric strap for which purpose the said strap is formed with a hollow boss 81 or barrel 81 receiving the enlarged head 83 of the eccentric rod against which a spring 82 bears at one end, the other end of said spring bearing upon a cap 84 screwed on to the boss 81. Through these connections the vibrator 55 is reciprocated so as to advance the contacting end 34 for the purpose of advancing the impression roll at the moment the marking device on the die carrier or marking head comes around into marking position. The 60 yielding connection is provided in order to

hold the vibrator with its contacting end in advanced position and with the impression roller up to its work for a sufficient length of time to enable the marking device to make the impression on the letter, it being noticed 70 that the marking devices consisting of the ribs and the die associated therewith occupy a considerable portion of the circumference of the marking head and it is therefore necessary to hold the impression roller forward 75 for the length of time occupied in the passage of the ribs and the die past the printing point and therefore the parts are so arranged that before the high part of the cam or eccentric arrives in line with the axis of the eccentric 80 rod the contacting end 34 will have advanced sufficiently to move the impression roller up to its work and this position will be maintained during the passage of the high part of the cam by the axis of the eccentric rod 85 and for an appreciable time after the said high part passes by the said axial line by reason of the employment of the spring 83 which allows the eccentric connection to yield under the greater pressure resulting 90 from the high part of the cam passing the axial line without doing damage or straining in any way the vibrator and the parts associated therewith.

The supplemental guard or registering 95 stop 48 is connected with a sleeve 85 arranged to turn about the shaft or pin 74 and having an arm 86 extending laterally, from which depends a pin or rod 87, the lower end of which has an opening 88 receiving an eccentric rod 89 of an eccentric 90 which is also on the main shaft 73 and is connected with and operated in unison with the eccentric 72 above mentioned. This eccentric rod 89 is provided with a shoulder 90 adapted in 100 the forward movement of the eccentric rod to strike the pin or rod 87 and thus turn the sleeve 85 so as to move the supplemental guard or stop 48 away from its normal position shown in Fig. 1 to the position shown in 110 dotted lines in Fig. 2, immediately following which the shoulder 90 moves back and away from the pin or rod 87 and a spring 92 acting on the arm 86 immediately returns the supplemental guard or stop finger to- 115 towards its normal position with the effects above described.

The main shaft 73 is driven in any suitable manner such as by a belt 93 and a pulley 94 and from this main shaft the shaft of the 120 impression roller is driven through gearing 95, 96, as shown in Fig. 7.

The friction feed wheel is driven by a gear 97 on its shaft 98, said gear being driven from a gear 99 on the main shaft.

The feed roll 22 is driven by a gear 100 on its shaft meshing with the gear 101 on the main shaft.

The feeding wheel 3 is driven from the shaft 98 of the friction feed wheel through 130

the belt 102 and the pulleys 103, 104. In driving the delivery wheel 56 the gear 105 is loosely mounted on its shaft 106, said gear meshing with the gear 107 on the main shaft. 5 There is another gear 108 on the shaft 106 of a different diameter from the gear 105 and meshing with the gear 99 and a clutch 109 is employed to connect either of said 10 gears to the shaft 106 in order to secure different speeds of the delivery rolls or wheels. 10 The delivery rolls or wheels are geared together through the gears 110 and 111 on their respective shafts.

In order to drive the stacking device 1 15 provide a gear 112 on its shaft 113, said gear meshing with a gear 114 on the shaft or pin 115 and meshing with the gear 108.

The supplemental device 70 is operated 20 through a belt 116 and pulleys 117, 118.

The clutch 109 is operated by a fork 119 connected with a vertically movable rod 120 having at its upper end a handle 121 adapted to raise and lower the said rod with the fork to shift the clutch. The handle is provided 25 with a boss 122 having a pin depending therefrom marked 123, which in one position of the handle is adapted to rest on the stand 124 and support the clutch rod in an elevated position, whereas when the handle is turned 30 to bring the pin 123 to an opening 125 in the said stand the pin dropping into said opening will allow the clutch rod to drop and shift the clutch from the upper gear to the lower gear, it being understood that the 35 handle 121 may turn on the clutch rod in order to secure the above actions. The purpose of this change speed is to cause long letters to be drawn away from the marking or printing members more rapidly than the 40 shorter letters thus preventing a second printing or marking action thereon at the rear end of the said long letter. This change of speed affects, it will be noticed, only the delivery rolls. One of these delivery rolls is 45 pressed by a spring against the other. Its shaft is pivoted at the lower end at 126 while at its upper end said shaft is journaled in a box 127 Fig. 1, connected with a stem 128 extending into a casing or box 129 on the under 50 side of the bed, said stem being pressed by a spring 130 within said casing. When the speed is changed as above to suit long letters the stacker must also be adjusted so that its action will be in proper time with the arrival 55 of the letter thereto. It will be understood that the stacker is timed in its movement so that as the letter is delivered from the rollers 56 and its front end arrives at the stacker, the abrupt shoulder or drop will be presented to the letter while the other letters 60 which were previously fed have been pushed or stacked laterally and are being borne upon by the high part of the stacker leaving thus a wide space between the stacked letters 65 and the fence 60 for the reception of the

next letter which moving into the open side of the scroll *i. e.* at which the abrupt shoulder is located will be the rapid rotation of the stacker immediately press the newly arrived letter laterally for the stacking opera- 70

Now when long letters are to be operated on and the speed of the delivery rolls is changed, as above described, the stacker must be adjusted so that its open side will 75 be presented to the newly delivered letter at the proper moment and for this purpose the stacker is loosely mounted on its shaft which shaft is provided with a collar 130* which may be raised slightly by the handle 130, 80 fixed on the same, to disengage the pin 131 of said collar from the hole 132 in the stacker, after which the stacker may be turned to bring another hole 133 below the pin 131 whereupon the collar may be 85 dropped and the said pin will then connect with the stacker in the new position to which it has been adjusted for long letters. The collar is splined to the shaft and a spring 130' presses it down, said spring bearing 90 against a nut 130' screwed onto the shaft.

Referring now to certain details of construction: A guide strip 134 extends along the pathway of the letters, which guides them from the feed rolls to the marking 95 members and thence to the delivery rolls. A spring guide 135 is also used for this purpose and a guide 136 for a similar purpose is attached to the bracket 51 and extends over one of the delivery rolls. The impression roller after being advanced is retracted by the spring 138, dotted lines Fig. 1, attached below the table and connected by a link 139 to a block 37, Fig. 5, in which the shaft of the impression roller bears. This 100 box extends up into the slideway or opening in the table top which permits the said impression roll to move towards and from the die carrier or rotary head. The forward movement of the impression roller is limited 110 to suit the thinnest letters by a stop collar 142 on the sliding barrel 42 striking against the rear end of the housing. The return movement of the locking-key or letter registering stop is limited by a stop 141 on the 115 fixed housing 31 as indicated in Fig. 6.

The inking roller 27 is of special construction represented in Fig. 5. The fabric covering its periphery is held in place between the flanges 143 which are screwed to the 120 block 144. This block is faced peripherally with rubber 145 upon which the fabric or felt periphery bears. The rubber surface prevents the fabric from creeping or piling up at any one point. This inking roller 125 may be set towards or from the die and canceling rib carrier for which purpose its pin 145* extends up through an opening 146 in the table top and it is carried by a lever 147 pivoted at 148 to the bottom of the table and 130

pressed by a spring 149. An adjustable stop limits the position of the said inking roller towards the marking head or printing roller 23.

Referring now to the eccentrics for driving the vibrator and the supplemental guard or stop finger it will be seen from Fig. 6 that these eccentrics are connected by a sleeve 149 loose on the main shaft, the eccentric 90 being attached to said sleeve by a screw 150 while the eccentric 72 is formed in one piece with the said sleeve. These eccentrics are driven through a gear 151 loose on the main shaft but connected to the lower eccentric 72 by the screw 152. This gear meshes with a gear 153 turning on a pin 154 of a bracket 155, said gear being attached by a sleeve 156 with a gear 157 which is driven by a gear 158 fixed on the main shaft. This gear train gives a two to one movement of the vibrator, 15 impression roller and supplemental stop in relation to the rotary marking head which latter, as above described, carries two sets of marking devices.

The canceling ribs are arranged on a block 25 adapted to yield against the action of the spring 158, Fig. 2. The outward movement of the block being limited by the pins 159 passing through the slots 160 of the projections 161 on the block.

30 I claim as my invention:—

1. In combination in a machine of the class described, marking means for the letters, a feed wheel, a yielding pressure device for holding the letters against the feed wheel and a retarding or separating device normally inactive but which engages a second letter upon the recession of the yielding device, substantially as described.

2. In combination in a machine of the class described, marking means for the letters, a feed wheel, a yielding smooth surfaced pressure device adjacent the feed wheel and a retarder in rear of the said pressure device having a friction surface 40 adapted to retard and separate the letters from the one being fed forward by the feed wheel, substantially as described.

3. In combination in a machine of the class described, means for marking the letters, a feed wheel having a channel or groove 45 in its periphery and a yielding pressure device for the letters arranged to extend slightly into the said groove or channel, the said pressure device and feed wheel being on opposite sides of the path for the letters substantially as described.

4. In combination in a machine of the class described, means for marking the letters, a feed wheel having a channel or 50 groove in its periphery, a yielding pressure device and a retarder or separator for the letters also having a groove or recess therein into which the said pressure device may recede, substantially as described.

5. In combination in a machine of the class described, means for marking the letters, a feed wheel, a pressure device for holding the letters against said feed wheel and a retarder having a recess therein into which the said pressure device may recede under the added thickness of a plurality of letters, substantially as described.

6. In combination in a machine of the class described, a marking head carrying means for marking the letters, an impression roller or platen, a combined letter-registering-stop and locking-key to register the letters and connect the platen with its setting mechanism and a vibrator for engaging the locking-key when the latter is set by a letter, said platen having a movable support independent of the support and operating means of the vibrator, substantially as described.

7. In combination in a machine of the class described, a marking head carrying means for marking the letters, an impression roller or platen, a combined letter-registering-stop and locking-key to register the letters and connect the platen with its setting means and a vibrator for engaging the locking-key when the latter is set by the letter, said vibrator being arranged and operating at one side of the impression roller, substantially as described.

8. In combination in a machine of the class described, a head carrying the marking means, an impression roll, a combined letter-registering-stop and locking-key, a yielding connection between said locking-key and the impression roller to accommodate letters of different thickness and means for operating the locking-key to advance the impression roller, substantially as described.

9. In combination in a machine of the class described, marking means for the letters, an impression roll or platen, a letter-registering-stop and locking-key combined, a vibrator for operating the locking-key, a connection between the said locking-key and the impression roll to advance the same, driving means for the vibrator and independent means for driving the platen, substantially as described.

10. In combination in a machine of the class described, means for marking the letters, an impression roller, a combined letter-registering-stop and locking-key, a vibrator for operating the locking-key and a connection between the said locking-key and the impression roll for advancing the same consisting of a member adapted to have movement towards and from the marking means and connected with the axis of the platen, said connection consisting of a movable part with a spring interposed between the same and the said movable member, substantially as described.

11. In combination in a machine of the class described, marking means, an impression roller, a combined letter-registering-stop and locking-key, a bracket or support 5 slidably mounted and a member movably carried by the said sliding member and engaging the axis of the impression roller and a spring interposed between the said sliding and the movable part carried thereby, substantially as described. 10
12. In combination, the marking means, an impression roller, a combined letter-registering-stop and locking-key supported independently of the movable support or carrier of the impression roller, a connection 15 between the said locking-key and the impression roller to move the same and means for operating the locking-key, substantially as described. 15
13. In combination, the marking means, an impression roller, a combined letter-registering-stop and locking-key, a pivot support for the same on the fixed part of the frame, means for operating the locking-key 20 and a connection between the said locking-key and the impression roller, substantially as described. 25
14. In combination marking means, an impression roller, a sliding member, a movable part thereon with a spring interposed between the same and the sliding member, said movable part engaging the axis of the impression roller, a combined letter-registering-stop and locking-key supported independently of the support and operating 30 means for the impression roller, the said locking-key engaging a part of the sliding member and means for operating the locking-key, substantially as described. 35
15. In combination, marking means, an impression roller, a sliding part connected with the impression roller, a locking-key to be set by the letters, a pivot support for said locking-key arranged independently of the 40 sliding part and means for operating the locking-key, said locking-key engaging a portion of the sliding member, substantially as described. 45
16. In a machine of the class described, marking means, a platen or roller, a reciprocating vibrator and a locking-key to connect the platen with the reciprocating vibrator when a letter is registered between the platen and the marking means, substantially as described. 50
17. In combination in a machine of the class described, marking means, a platen or roller, a reciprocating vibrator and a locking-key to connect the platen with the reciprocating vibrator when a letter is registered between the platen and the marking means and means for operating the reciprocating vibrator consisting of a crank or face wheel with a pitman connecting the 55
- same with the reciprocating vibrator, substantially as described. 60
18. In combination with the marking means, a platen, a letter-registering-stop a supplemental stop or guard coöperating therewith, said supplemental stop arresting the progress of the letter between the marking means and platen when the main registering-stop is free to permit the untimely passage of the letter, substantially as described. 65
19. In combination, marking means, a platen, a letter-registering-stop, a supplemental guard or stop and means for operating the same, said supplemental guard or stop serving to free the letter from the main stop, substantially as described. 70
20. In combination, marking means, a platen, a main registering-stop for the letter having a hook or like bearing for the letter and a supplemental guard or stop for the letter to obstruct the passage of the letter when the main stop is free, the said supplemental stop serving also to move the letter from the hook bearing part, substantially as described. 75
21. In combination, marking means, a platen, a main registering-stop for the letter serving also as a locking-key, means for operating the same to advance the platen and to subsequently move the said registering-stop 80 to permit the passage of the letter, a supplemental guard or stop to arrest the passage of the letter arriving at improper time, with means for operating it out of the path of the letter when the main registering-stop is 85 operated to allow the letter to pass, said supplemental stop or guard returning towards its normal position to free the letter from the main registering-stop, substantially as described. 90
22. In combination with marking means, a platen movable towards and from the marking means, constantly driven means for moving the platen, a letter registering stop and locking key, and a yielding gate co-operating therewith to register the letter and hold the letters arriving at improper time, said locking key being normally held out of the path of the said constantly driven means and moved into said path by the letter to 95 thereby connect the platen with its operating means, substantially as described. 100
23. In combination, marking means, a platen, a main registering stop for the letter, a supplemental stop or guard to arrest the letters arriving at improper time and a yielding gate coöperating with the main and supplemental stops, substantially as described. 105
24. In combination with marking means, a platen, a main and supplemental stop operating on one side of the pathway of the letter and a yielding gate operating on the 110
- 115
- 120
- 125

opposite side of the pathway of the letter and coöperating with the main and supplemental stops, substantially as described.

25. In combination, marking means, a platen, a letter-registering-stop acting as a locking-key and driving connections to operate against said locking-key to advance the platen, said driving connections having a yielding portion whereby the platen will 10 be maintained against the marking means for the required period, substantially as described.

26. In combination, marking means, a platen, means for moving the said platen towards the marking means consisting of an eccentric and yielding connections between the same and the platen whereby the platen will be maintained in its forward position for a period before and after the time when 20 the high part of the eccentric is passing the center, substantially as described.

27. In combination, marking means, an impression roller or platen, means for operating the same, comprising a reciprocating 25 member situated to one side of the platen and a locking-key intermediate the same and the platen, substantially as described.

28. In combination marking means, a platen and means for operating the same 30 consisting of the combined letter stop and locking-key, a reciprocating member located to one side of the platen, an eccentric and connections from the same to the said oscillating member, substantially as described.

35. 29. In combination, the rotary head having marking means thereon, a platen, means for moving the platen to the marking means consisting of a member arranged below the marking head, a locking-key and connection 40 between the said locking-key and the said operating means.

30. In combination, the marking head, the platen, a locking-key, a reciprocating vibrator, an oscillating crank or face plate journaled to one side of the platen and an eccentric below the marking head connected with the oscillating crank or face plate, substantially as described.

31. In combination, the marking head, a 50 platen, a locking-key, a member journaled to one side of the platen arranged to operate the locking-key, a supplemental stop, means carrying the same arranged to turn concentric with the operating member for the locking-key, and means for operating the said carrying member, substantially as described.

32. In combination a marking head, a platen, a member journaled to one side of the platen for operating the locking-key, a 60 supplemental stop, a journaled carrier there-

for, an eccentric for operating said carrier and an eccentric for operating the said member, substantially as described.

33. In combination, the marking head, a platen, a main registering stop, a supplemental registering stop and a yielding gate having shoulders for the said stops, substantially as described. 65

34. In combination a marking head having a plurality of sets of marking devices 70 thereon, a platen, a vibrator for operating the platen and means for operating the marking head, and vibrator in a relation of two to one so that a plurality of complete vibrations of the vibrator for each rotary 75 movement of the marking head takes place, substantially as described.

35. In combination in a machine of the class described, means for printing upon the letters, delivery rolls, change speed mechanism, a stacker and means for setting the stacker to correspond to the speed of the delivery rolls, substantially as described. 80

36. In combination in a machine of the class described, means for printing upon the letters, delivery rolls, change speed mechanism, a stacker and means for setting the stacker to correspond to the speed of the delivery rolls, substantially as described. 85

37. In combination in a machine of the class described, a marking head, a platen, a combined letter - registering - stop and locking-key, a vibrator to operate the locking-key upon the timely arrival of a letter and to lock the locking-key upon the untimely 95 arrival of a letter, substantially as described.

38. In combination in a machine of the class described, a marking head, a platen, a combined letter - registering - stop and locking-key, a vibrator to operate the locking-key upon the timely arrival of a letter and to lock the locking-key upon the untimely arrival of a letter, said vibrator presenting its side portion to the locking-key for the locking effect, substantially as described. 100

39. In combination in a letter marking machine a rotary marking head and a platen normally separated, a locking key and registering stop in the path of the letter and means for securing a closing movement between the platen and marking head, said means acting upon the locking key for transmitting the closing movement therethrough, substantially as described. 105

In testimony whereof I affix my signature 115 in presence of two witnesses.

SAMUEL J. EVANS.
